[57] CLAIM

The ornamental design for an edge supported supermarket cart cupholder, as shown and described.

DESCRIPTION

FIG. 1 is a perspective view of an edge supported supermarket cart cupholder embodying our new design;

FIG. 2 is a top plan view thereof;

FIG. 3 is a front elevational view thereof;

FIG. 4 is a first side elevational view thereof;

FIG. 5 is a second side elevational view thereof;

FIG. 6 is a rear elevational view thereof; and,

FIG. 7 is a bottom plan view thereof.

FIG. 8 is an enlarged top perspective view thereof.

The dotted line representations form no part of the claimed design.
